UNITED STATES PATENT OFFICE.

CHARLES ALBERT WETTENGEL, OF ST. LOUIS, MISSOURI, ASSIGNOR TO AMERICAN ZINC, LEAD & SMELTING COMPANY, OF ST. LOUIS, MISSOURI, A CORPORATION OF MAINE.

CONDENSER.

Application filed March 4, 1918. Serial No. 220,389.

To all whom it may concern:

Be it known that I, CHARLES ALBERT WETTENGEL, a citizen of the United States, residing at the city of St. Louis and State of 5 Missouri, have invented a new and useful Condenser, of which the following is a specification.

This invention relates to condensers of the type adapted for use for redistilling spelter 10 or galvanizers zinc drosses.

The ordinary grade of zinc contains a percentage of impurities, principally lead and iron. This grade of zinc is not suitable for use for many purposes for which pure 15 zinc is used, as, for instance, for brass for spinning and deep drawing, since zinc for these purposes must contain a very small percentage of impurities, probably less than one-fourth of one per cent.

20 The present invention relates to the art of redistilling zinc to separate the zinc from other metals. The process of redistilling is really a fractional distillation which separates the zinc from other metals having 25 higher boiling points. Metallic zinc boils at about 925° C., and the vapor can be condensed into metallic zinc by maintaining the proper conditions for that result. Ordinary zinc which contains lead and iron as 30 impurities is used as a starting point. The zinc is volatilized in a retort from which the zinc vapor passes off into the condenser and is condensed as approximately pure high grade zinc. The lead and iron do not 35 vaporize at as low a temperature as the zinc and they remain in the retort. The quantity of lead and iron is relatively small and it is desirable not to open the retort by removing the condenser for the purpose of putting 40 into each retort a fresh supply of zinc, because of the large loss of zinc due to oxidation. Hence, if the condenser is placed and the joint between it and the retort sealed it is desirable to leave it as long as possible; 45 and in the use of my invention the procedure is to supply zinc, replacing the evaporation by zinc bars which are inserted through an opening provided for that purpose in the outer end of the condenser and 50 passed into the retort.

An object of my present invention is to provide a condenser of novel and efficient construction for redistilling zinc in accordance with the practice above explained.

Another object is to provide an improved 55 condenser of the character mentioned in which the cold zinc may be introduced in small quantities and at frequent intervals in order not to chill the bath of molten zinc in the retort without the necessity of first 60 drawing the melted metal from the condenser.

Numerous advantages of my invention will be apparent from the detailed description of an embodiment thereof as illustrated 65 in the accompanying drawing, in which

Fig. 1 is a longitudinal sectional view illustrating my invention in connection with a furnace.

Fig. 2 is an end elevation.

As shown in the drawing my improved condenser is embodied in a zinc smelting furnace constructed to support the inner ends of the retorts below the open ends thereof.

The retorts 1 are supported in inclined positions, being preferably of cylindrical form and having their inner lower ends closed by integral end walls. The retorts are of the usual ceramic material and are 80 adapted to receive the zinc bars which are melted with the result that the zinc vapor passes into the condenser, leaving as deposits in the retort the impurities which have a higher boiling point than the zinc.

The upper ends of the retorts 1 are open and receive the smaller ends of the tapering condensers 2. The upper walls of the condensers within the open ends of the retorts form shoulders or offsets below the 90 surfaces of the upper walls of the retorts. The joint around the condenser at its connection with the retort is sealed as indicated at 3 to prevent any loss of the zinc vapor by leakage. The inner tapered end of 95 each condenser is provided with a bridge or dam 4 which may be formed integrally with the condenser, or cemented in position, as desired.

The outer end of the condenser is provided with a wall 5 having an opening 6 through which the zinc bars may be inserted and passed over the bridge or dam into the retort. The wall 5 is also provided with an opening 7 at the lower side of the condenser for the purpose of withdrawing the molten zinc. When the condenser is in use the openings are closed or sealed in an ap-

propriate manner as, for instance, by a mixture forming a loam or stuffing which, while in a plastic condition may be inserted in the openings, and which when dried is frangible and has sufficient strength to withstand the pressure of the molten zinc but which may readily be broken out without breaking the condenser; or, said openings may be closed by removable plugs 8 of ceramic or other appropriate material.

In operation the zinc is volatilized in the retorts 1 and passes into the condensers 2 in which condensation takes place principally on the inner surface of the condensers 15 not covered by the molten zinc. In the use of condensers of the type heretofore usually employed the rapid reduction of surface as the condenser accumulated a stock of molten zinc frequently resulted in explosions, because the generation of the zinc vapor continued at the same rate and the smaller surface in the condenser was unable to condense the vapor as fast as generated, resulting in accumulation of pressure that would cause 20 an explosion. In using condensers of that old construction it was impossible to charge the retort without drawing the molten metal previous to each charge. The operation of drawing the molten metal from such condensers is laborious and requires skill, so that by producing a condenser which requires less frequent drawing of the molten metal, considerable advantage is gained in the saving of labor; although in any instance the drawing must be frequent enough to prevent dangerous explosive pressure within the retort and the condenser.

My improved condenser is of such size that it will hold a greater quantity of molten zinc and still have an ample surface exposed for the condensation of the zinc vapors produced, and the provision of the two openings 6 and 7 in the forward wall of the condenser permits the molten zinc to be withdrawn through one end and the other opening to be used for supplying the cold zinc bars into the retort for redistilling. The placing of the opening 6 at the top en-

ables the bars to be fed into the retort without first drawing the metal from the condenser. These advantages are obtained by making a condenser much larger size than the ordinary condenser and providing the two openings at the exposed end, the opening 7 serving for the withdrawal of the molten zinc and the opening 6 serving as a passage through which the zinc bars may be passed into the retort over the bridge 4.

I claim:

1. A tapering condenser having a fixed head provided at its larger end with an opening for withdrawing the molten metal, and another opening at its larger end through which the zinc bars may be passed into the retort. 60

2. A condenser having a fixed head provided with an opening for withdrawing the molten metal, and another opening through which the zinc bars may be passed into the retort; and a bridge or dam across the inner end of the condenser at the lower side thereof. 70

3. A condenser having a bottom wall inclined downwardly and outwardly; a fixed head at the outer end of the inclined wall provided with a plurality of openings; and a bridge or dam across the inner end of the condenser at the lower side thereof. 75

4. A condenser having a fixed head provided with a series of openings at its drawing end. 80

5. A condenser constructed of ceramic material having at its retort end an integral bridge, and having its upper wall out of alignment with the upper wall of the retort, and having an integral head at its drawing end, there being charging and drawing openings formed in said head; and a ceramic closure for said drawing opening. 85

6. In combination with a retort, a condenser having at its retort end a fixed bridge and out of alignment with the wall of the retort, and said condenser having a fixed head at its drawing end and provided with a drawing opening and a charging opening. 90

CHARLES ALBERT WETTENGEL. 95
